UNITED STATES PATENT OFFICE.

CHARLES BOOZ, OF BUFFALO, NEW YORK, ASSIGNOR, BY MESNE ASSIGN-
MFNTS, TO GEORGE K. BIRGE, OF SAME PLACE.

DESIGN FOR WALL-PAPER.

SPECIFICATION forming part of Design No. 24,840, dated November 5, 1895.

Application filed September 30, 1895. Serial No. 564,226. Term of patent 3½ years.

to all whom it may concern:

Be it known that I, CHARLES BOOZ, a citizen of the United States, residing at Buffalo, in the county of Erie and State of New York, have invented and produced a new and original Design for Wall-Paper, of which the following is a specification, reference being had to the accompanying drawing, showing a part thereof.

The design consists of a series of oblong panels connected together by horizontal and vertical lines, with three parallel lines running horizontally between said panels and a palmette or Grecian style of ornament arranged in the center of each panel, as represented in the accompanying drawing.

The border of the design is formed of a series of large palmette or Grecian style of ornaments placed between groups of parallel

lines running vertically and horizontally, the two outer vertical lines terminating at the top in scrolls, as shown. Ornamental scrolls form the base of the ornaments, with lines running parallel with said scrolls and ending in keywork of Grecian style, as shown in the drawing.

What I claim is—

1. The design for wall paper herein shown and described.
2. In the design for wall paper, the border herein shown and described.

Witness my hand this 27th day of September, 1895.

CHARLES BOOZ.
